FIGURE 1 is a front elevational view of a mobile telephone or similar article, showing my new design;

FIGURE 2 is a left side, top and front perspective view;

FIGURE 3 is a left side elevational view; and

FIGURE 4 is a right side, bottom and rear perspective view thereof.

The dominant feature of my design resides in the dis-
closed configuration of the tubular housing which is at-
tached to one side of the casing and which accommodates
the hand set.

I claim:

The ornamental design for a mobile telephone or simi-
lar article, as shown and described.
